US0D1042023S

(12) **United States Design Patent** (10) Patent No.: **US D1,042,023 S**
(45) Date of Patent: ** Sep. 17, 2024

(54) **BOTTLE LID**

(71) Applicant: **Ningbo Zhongnuo Plastic Products Co., Ltd.**, Ningbo (CN)

(72) Inventor: **Wenliang Xu**, Huainan (CN)

(73) Assignee: **NINGBO ZHONGNUO PLASTIC PRODUCTS**, Ningbo (CN)

(**) Term: **15 Years**

(21) Appl. No.: **29/843,499**

(22) Filed: **Jun. 22, 2022**

(51) LOC (14) Cl. **07-01**

(52) U.S. Cl.

USPC **D7/396.2; D7/392.1**

(58) **Field of Classification Search**

USPC D6/515; D7/321, 391, 392, 392.1, 396.1, D7/396.2, 507, 509, 510, 511, 523, 608, D7/900; D9/435, 440, 442, 443, 444, D9/445, 446, 447, 448, 449, 450, 454, D9/531, 682, 683, 684, 685, 686, 687, D9/688, 689, 690, 691, 692, 693, 694, D9/723

(57) **CLAIM**

The ornamental design for a bottle lid, as shown and described.

DESCRIPTION

FIG. 1 is a front and top perspective view of a bottle lid, showing my new design;

FIG. 2 is a rear and bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof; and,

FIG. 9 is another perspective view thereof, shown in an alternative position.

The broken lines in the figures illustrate portions of the bottle lid that form no part of the claimed design.

1 Claim, 9 Drawing Sheets
